UNITED STATES PATENT OFFICE

GEORGE P. HAYNES, OF BROOKLYN, NEW YORK, ASSIGNOR TO TODD DRY DOCK ENGINEERING AND REPAIR CORPORATION, OF NEW YORK, N. Y., A CORPORATION OF NEW YORK

APPARATUS FOR BURNING PULVERIZED COAL

Application filed August 10, 1927. Serial No. 211,940.

This invention relates to means for burning pulverized coal in furnaces, and my improvements are directed to a new system wherein a furnace or each of a number thereof serving a Scotch or other type of boiler is provided with a complete unit for attachment to a furnace front, each unit including a pulverizer, a fan and a prime mover that drives said pulverizer and fan; the furnace front being adapted to control the delivery of a supply of heated air for combustion, and the fan providing an air supply as a vehicle for conveying the powdered coal from the pulverizer to the zone of combustion. Still further each unit is adapted for the removable placement of a burner wherewith fluid fuel may be used to start the fire or to permit operation either on fluid fuel alone or with both fluid fuel and pulverized coal.

Also my invention comprehends the provision of controlled means for the continuous delivery of comminuted coal into a hopper from which the coal passes by gravity into the pulverizers forming a part of respective units.

Other features and advantages of my invention will hereinafter appear.

In the drawings:

Figure 1 is a transverse sectional view of a steamship equipped with my improved unit system for delivering fuel to the boilers, each boiler including a plurality of furnaces, certain coal conveying and depositing means being shown in section.

Fig. 2 is a vertical central sectional view, partly in elevation of one of the feeding units and associated parts.

Fig. 3 is an enlarged elevation of a boiler and a single feeding unit applied thereto with the hopper shown in section, and

Fig. 4 is an enlarged section taken on the line 4—4 of Fig. 2.

In the example of my invention herein illustrated I have indicated a steamship as equipped with a series of boilers each provided with a number of furnaces all arranged athwart ship, each furnace having its own pulverizing and supply unit, all of which are served with comminuted coal

from a common hopper which is continuously replenished by conveyer means.

Thus, in Fig. 1 let 1 indicate the hull of a steamship, 2 the boilers therein and 3 the furnaces for said boilers. Extended across the front of the boilers, above the furnace fronts, is a hopper 4, and at opposite sides thereof are endless conveyers 5, operating over gears 6 and adapted to deposit in the hopper comminuted coal which has been dumped into the chute 7. It will be understood that the coal thus deposited in the hopper is to be distributed therein by suitable trimming means which may be either manual or mechanical.

Pendent from the base of hopper 4 is a series of vertical tubes 8 each terminating in a flange 9, and each provided with a control means 10, said tubes being adapted, when the control means are open, to deliver the comminuted coal by gravity from the hopper to respective pulverizers comprised in the furnace feed units.

In Fig. 2 there is shown in side sectional elevation a furnace front comprising the back plate 11 having an annular flange 12 adapted to fit within the forward portion of the furnace, to which plate 11 is suitably attached, said plate having a central opening 13 to coincide with the flared opening 14 through the brick which constitutes the fuel entrance into the furnace.

The plate 11 is part of the hollow furnace front, said furnace front having the partially surrounding wall 15, inturned flange 16, and inner co-axial wall 17, spaced from wall 15, to constitute the heated air supply space 18 usual with this type of furnace front. Also the inner wall 17 is provided with ports 19 for the passage of heated air to the furnace interior, to support combustion, and an annular ring 20, having ports 21 therein is revolvably mounted upon wall 17 to control the air supply. Operating means for ring 20 are shown at 20a, Fig. 4.

The elements of the furnace front thus far described are substantially according to usual practice and in themselves form no part of my present improvement. The inturned flange 16, affords a base or mount for

a plate 22, which is secured thereto by bolts 22a, and provides a complete front closure means for the heated air space 18. Said plate 22, has an outwardly extending annular flange 23 that projects a certain distance from the furnace front, and it also has an aperture 24 communicating with air supply space 18, all for purposes to be described hereinafter.

10 It will be noted that I have provided a horizontally disposed bracket 25, secured as by the bolts 25a to the lower portion of plate 22, and thus to the furnace front. This bracket serves as a support upon which to 15 seat one of my improved fuel supply units in its associated relation with a furnace front, said unit having flanges 26 secured as by bolts 26a to said bracket.

The unit housing 27 is provided with a bearing 28 for an axially disposed hollow shaft 29, and to said shaft is secured the hub portion 30 of a radial pulverizer having the conoidal portion 30a carrying disks 31 provided with beaters 32 revoluble within 25 steel linings 33. Each unit pulverizer is provided with a feed pipe 34, having a flange 35, by which it is bolted to the flange 9 of a tube 8, to thereby receive a supply of coal from the hopper 4, the pipe 34 having a 30 delivery end 36 directed into the pulverizer and also having an annular flange 37 by which it is secured to the housing 27. It will be seen that the lower portion of the feed pipe 34 is inclined in a downwardly 35 forward direction and that the lower wall of said pipe merges into the conoidal central portion 38 over which the pulverizer rotates.

Secured to the forward end of hub 30 is an annular plate 39, to be rotatable there- 40 with, said plate lying in spaced relation to the outlet 40 from the pulverizer, and said plate carrying a fan 41 that functions to pull the powdered coal from the pulverizer. A tube 42, connecting the heated air supply

45 space in the furnace front with the coal feed pipe 34, said tube having a control valve 43, permits an air stream to flow through the pulverizer as a vehicle for the powdered coal in response to the fan operation. A 50 deflector 42a extends at a downward angle into feed pipe 34, from the top of the aperture 42b therein, that connects with tube 42 to direct the flow of air toward the pulverizer. The air stream, laden with powdered 55 coal, is delivered whirling by the fan into an annular space 44 formed in housing 27, and thence passes, still whirling, through a conoidal passage 45 formed between the forward wall 46 of housing 27 and an angled 60 ring 47 carried by plate 39; continuing from said passage into a delivery tube 48, that projects from wall 46, toward the furnace opening 14.

An air cone 49 having openings 50 there- 65 through provided with angled vanes 51, is

slidably mounted on tube 48, said air cone being actuatable by manually operable rods 52 in its movement to and from the front plate 13, thereby regulating the admission of air into the furnace from the heated air supply space 18 to support combustion of the fuel.

Also associated with each unit is a prime mover for revolving shaft 29 at high speed, and as an example of such prime mover I 75 have shown a steam driven turbine having the casing 53 and rotor 54 with blades 55. The casing is represented as connected to the housing by means of brackets 56 which are secured to the housing by bolts 57, the casing part 58 having an end bearing 28a for shaft 29. The rotor 54 is directly connected to the shaft 29 for its rotation.

Usual means, such as a grid (not shown) in the base of hopper 4 may be provided for 85 sizing the coal that is permitted to pass by gravity to the respective pulverizers.

At 59 and 60 I have indicated a main pipe line with branches 60a, each provided with a control valve 61 for delivering steam to the respective turbines for their operation, and it will be appreciated that by closing the controls 10 and 61 for one or more of the units a boiler equipped with a plurality of furnaces can be operated at reduced 95 capacity, such as for maneuvering purposes.

The steam exhaust means is shown at 62, and steam may be returned therefrom direct to the condenser (not shown).

Removably entered through the hollow 100 shaft 29 is an oil burner 63 having an atomizing nozzle 64 that is projected through the delivery tube 48, axially thereof, for delivering an oil flame into the furnace, the oil burners for each unit being supplied with oil by means of a main pipe line 65, having branches 66 for the respective burners, and a return line 67, each branch being provided with a control valve 68.

The oil burners are intended primarily 110 for ignition purposes their flames serving to fire the pulverized coal when the turbine is set in motion and the pulverizer operated. Then the oil supply can be shut off and the burners removed. Also the oil burners can be operated when a vessel equipped with the dual coal and oil system is engaged in maneuvering and the consumption of fuel is relatively small. Furthermore as will be understood the oil burning equipment supplementing that for coal burning in each 115 unit permits operation with whichever form of fuel is most readily available.

Each oil burner is provided with centering devices such as are indicated at 69; said centering devices being carried by the burner tube to be removably entered therewith into the hollow shaft 29. Besides serving to center the burner within the hollow shaft 125 the devices 69; which may have means of 120

anti-frictional relation with said shaft, thereby prevent the high speed rotation of the shaft from effecting excessive wear between the shaft and burner during the relatively brief periods while the burner is in its operative position for initial heating and ignition purposes.

It is to be understood that while I have herein described and illustrated oil burning means for use in initially heating a furnace where pulverized coal is intended to be employed as fuel, and for igniting such fuel, my invention is not to be limited thereby as any other liquid or gaseous fuel, in place of oil, may be employed for such purpose, without departing from the general character of my invention with respect to the use of pulverized coal as fuel for operating a Scotch boiler.

Variations within the spirit and scope of my invention are equally comprehended in the foregoing disclosure.

I claim:

1. A fuel-pulverizing-feeding unit, for attachment to a furnace adapted for the burning of pulverized fuel, comprising a shaft mounted in bearings carried by said unit, a pulverizer concentrically mounted on said shaft and having an impact rotor which is carried by said shaft, a feed conduit adapted to supply granular fuel to the pulverizer, means for supplying regulated quantities of pre-heated air to the fuel in its passage through said conduit and for assisting the flow thereof, a blower, including a fan mounted on said shaft and a hollow casing surrounding the same, which blower has an inlet connecting with the outlet of said pulverizer whereby pulverized fuel is discharged into said blower from the pulverizer, and means for connecting said blower with a pulverized fuel burner of a furnace, said unit being bodily removable from a furnace to which it may be attached and conveniently replaceable by a similar unit when desired.

2. The combination with a furnace for burning pulverized fuel, said furnace having a hollow front and means for supplying air thereto, of a fuel pulverizing feeding unit attached to said front, said unit comprising a shaft related axially to said front and mounted in bearings carried by said unit, a pulverizer concentrically mounted on said shaft and having an impact rotor which is carried by said shaft, a feed conduit adapted to supply granular fuel to the pulverizer, means for supplying regulated quantities of pre-heated air from said hollow front to the fuel in its passage through said conduit and for assisting the flow thereof, a blower, including a fan mounted on said shaft and a hollow casing surrounding the same, which blower has an inlet connecting with the outlet of said pulverizer

whereby pulverized fuel is discharged into said blower from the pulverizer, and means for connecting said blower with a pulverized fuel burner of a furnace, said unit being bodily removable from a furnace to 70 which it may be attached and conveniently replaceable by a similar unit when desired.

Dated, New York, August 2nd, 1927.
GEORGE P. HAYNES.
